UNITED STATES PATENT OFFICE.

ROBERT E. WILSON, OF CHICAGO, ILLINOIS, ASSIGNOR TO STANDARD OIL COMPANY,
OF WHITING, INDIANA, A CORPORATION OF INDIANA.

FURNACE FOR THE TREATMENT OF SPENT FULLER'S EARTH.

Application filed February 23, 1924. Serial No. 694,776.

The present invention relates to apparatus suitable for use in the treatment of spent fuller's earth, and more particularly to improvements in rotary furnace kilns and like devices for roasting or calcining spent fuller's earth prior to reuse. It will be fully understood from the following description, illustrated by the accompanying drawings in which:

10 Figures 1^a and 1^b together show in side elevation a rotary kiln constructed in accordance with the invention, Fig. 1^a showing the end connected with a stack and Fig. 1^b showing the opposite end;

15 Fig. 2 is an end elevation of the kiln partly broken away; and

Fig. 3 is a vertical sectional view through the end of the kiln shown in Fig. 2.

Referring more particularly to the drawings, the numeral 5 indicates the shell of a 20 rotary kiln, mounted in the usual manner upon rollers 6 and driven by a suitable prime mover 7 operating through an encircling gear. At one end the shell of the kiln rotates in a head 8 secured in a suitable flue or stack setting 9. A suitable chute 10 or 25 other means is provided at this end of the furnace for the supply of the spent fuller's earth to be treated thereto.

30 The rotary furnace is downwardly inclined from this end, and at its opposite end is rotatably mounted in a casing or support 12, which receives the material upon discharge from the furnace and in turn discharges it through a chute or opening 13. An opening 14 is provided in the casing for 35 the introduction of a suitable heating means, for example, a gas or oil burner.

At one side of the opening 14 and some- 40 what below it a pipe 15 passes through the head of the casing 12 and extends into the rotary furnace for substantially the entire length thereof, and is substantially parallel to its axis. At intervals branch pipes 16 45 are drawn off from the pipe 15 and extend downwardly to the lower side of the shell, and thence along the interior surface of the shell in the direction thereof and in planes substantially perpendicular to its axis. 50 These pipes are capped at their ends and are provided with perforations on their lower surfaces. They are so disposed as to lie in the bed of material formed in the furnace during the operation thereof and are spaced at their ends by the pipe 16^a. This

bed is maintained by means of the annular plate 17 secured to the rotary kiln at its discharge end. As shown in Fig. 2 the bed banks up on one side, and the perforations of the pipes 16 are normally located within 60 the banked bed.

In the operation of the kiln, spent fuller's earth or similar material to be calcined is fed in continuously through the chute 10 and travels gradually through the rotating 65 kiln of the furnace, which is rotated by means of the prime mover 7 at any desirable rate. The annular plate 17 at the discharge end of the furnace serves to maintain a bed of the material within the furnace, this bed covering the perforated pipes 16. The annular plate 17 may be six to eight inches in width, thereby maintaining a corresponding depth of material in the rotating furnace. Air is forced in through 75 the pipe 15 and the distributing pipes 16, a suitable pressure being from five to ten pounds. The air violently agitates the fuller's earth being calcined and materially aids in the combustion and removal of the carboaceous matter contained therein. The calcining material is brought to a temperature preferably not in excess of 1500° F., and suitably from 1100 to 1300° by the heating means (not shown) introduced through 80 the opening 14 together with the heat evolved by the combustion in the clay. The amount of heating medium required is materially reduced. The pipes 16 are spaced apart at suitable intervals; for example, intervals of 6 to 12 inches have been found satisfactory in a five foot rotary kiln or 85 furnace.

I claim:

1. A rotary furnace comprising an inclined rotatable shell, means for rotating the shell, means for supplying spent fuller's earth at the upper end thereof, means for supplying heat internally within said shell, an air conduit leading into the shell and a 90 distributing pipe leading from said conduit to the lower side of the shell and thence in close proximity to the wall thereof in the direction of rotation of the shell, said distributing pipe being provided with perforations in the portion normally covered with the fuller's earth.

2. A rotary furnace comprising an inclined rotatable shell, means for rotating the shell, means for supplying fuller's earth 95

at the upper end thereof, an annular plate at the lower end of the shell for maintaining a body of treated material therein, means for supplying a heating medium within the shell, an air pipe extending longitudinally within the shell and a plurality of distributing pipes leading from said air pipe to the

lower side of the shell and thence in close proximity to the wall thereof in the direction of rotation of the shell, said distributing pipes being provided with perforations in the portions normally covered with the fuller's earth. ¹⁰

ROBERT E. WILSON.
